UNITED STATES PATENT OFFICE.

HAROLD W. PATTISON, OF SEATTLE, WASHINGTON.

AUTOMATIC CONTINUOUS-RAIL CROSSING.

1,344,957.

Specification of Letters Patent. Patented June 29, 1920.

Application filed February 10, 1920. Serial No. 357,538.

To all whom it may concern:

Be it known that I, HAROLD W. PATTISON, a citizen of the United States, residing at Seattle, in the county of King and State of Washington, have invented certain new and useful Improvements in Automatic Continuous-Rail Crossings, of which the following is a specification.

My invention relates to improvements in railroad crossings and more particularly to means arranged at the intersecting points of the crossing and forming a part thereof, that will eliminate the jolting and jarring of cars passing thereover, and likewise reduce the noise and wear on the same.

A further object of the invention lies in the provision of a device of the above mentioned character having filler blocks pivotally mounted in gaps formed adjacent the intersecting point of each rail which are automatically actuated by the wheels of the train approaching the crossing, said blocks having means associated therewith, whereby they are normally held in a vertical position to form a continuation of the rails on which the train is traveling.

A further object of the invention lies in the provision of a structure of the above mentioned character wherein the gap-filling blocks or elements are so positioned and supported that they may be readily removed from the crossing for repair or replacement, thus increasing the practicability and efficiency of the same.

Other objects and advantages of the invention will be apparent during the course of the following description.

In the accompanying drawings forming a part of this specification and in which like numerals are employed to designate like parts throughout the same,

Figure 1 is a plan view of a crossing embodying my improvement;

Fig. 2 is a section through one of the intersecting portions of the crossing showing the detail arrangement and structure of the gap-filling blocks used in connection therewith;

Fig. 3 is a perspective view of one intersecting portion with the gap-filling blocks removed;

Fig. 4 is a detail perspective view of the clamping block, and

Fig. 5 is a detail perspective view of one of the gap-closing blocks.

In the drawings, wherein for the purpose

of illustration I have shown a preferred embodiment of my invention, the letters A and B designate two tracks extending at right angles to each other and intersecting at the crossing C. The rails 5 of the track A and the rails 6 of the track B are provided with the usual gaps 7 adjacent their intersecting points to permit the passage of the flange on the wheels of the car moving over the tracks, without the crossing rails interfering. As is obvious in railroad crossings there are four intersecting points and since each section is of identically the same structure a description of one in this instance will suffice.

Referring to my invention, the numeral 8 indicates a filler block or gap-closing element which is of a configuration to conform to that of the rail tread being mounted within the gap 7 adjacent the intersecting point of the rails. This element is more clearly illustrated in Fig. 5 and as will be seen has two trunnions 9 extending from opposite sides thereof forming journals. 80 The ends of the rails at the gap are provided with centrally positioned elongated openings 10 which form a bearing for one of the journals 9 of the gap-closing elements 8, as clearly shown in Fig. 2. The center of the 85 intersecting point of the rails is recessed as at 11, said recess terminating approximately midway the depth of the rails and having cut from its edges bearings 12 which 90 extend at right angles to each other. These 95 bearings 12 receive the oppositely extending journals 9 of the filler blocks 8 so that the blocks are pivotally mounted within the gaps and are capable of pivotal movement. The purpose in having the openings 10 in the ends of the rails elongated, is to permit the ready removing of the journals from their bearings when desired. In order that the filler blocks will be securely held in their bearings, a clamping block 13 is shaped to 100 fit within the recess 11 and has two bearings 14 cut from its edges corresponding to the bearings 12 and forming a continuation thereof. This block is provided with a laterally projecting extension 15 which is seated in the cut-out portion 16 of the rail 6 to which it is securely attached by means of a bolt 16' which passes through the aperture 17. The function of this clamping block is to permit the removal of the gap-closing elements, should they need repair or 110 become inoperative.

Each intersecting portion of the rails is mounted upon a bed plate 17 which extend parallel therewith and in this instance are supported upon the rail ties 18. Each plate 5 is provided with a pair of depressions 19 forming pockets 19' directly beneath the gaps 7, as clearly shown in Fig. 2. These depressions are embedded in the tie 18 and serve to hold the plate 19 securely in position, as well as performing the function for which they are adapted. Each filler block 10 8 has depending from its lower edge an apertured lug 20 to which is attached one end of the retractile spring 21 which extends 15 downwardly within the pocket 19' and has its opposite end attached to an upwardly projecting apertured lug 22. The purpose in providing the pocket 19' is to afford a 20 stronger spring action for returning the filler gaps to a vertical position when moved downwardly and to overcome the vibratory movements to which the blocks are subject. It might also be well to mention that the 25 filler blocks 8 are counterbalanced, so that ordinarily very little spring action is necessary to return them to their normal position.

In describing the operation of the invention it will be assumed that the train is 30 traveling on the track A which on reaching the crossing, the flanges of the wheels will move the filler blocks of the track B downwardly while the filler blocks 8 of the track A will form a continuation of the track upon 35 which the train is traveling. This will avoid the usual jarring or jolting of the car caused by the passing of the same over the usual gaps at the intersecting portions of the crossing. Immediately after the train has 40 passed over the crossing the springs 21 will return the filler blocks to their vertical position instantly. The operation of the improvement is identically the same when the train is traveling on the other track except 45 the filler blocks of the track A are depressed while the filler blocks of the track B form a continuation of the track upon which the train is traveling. This arrangement eliminates the usual noise of the train moving 50 over the crossing and likewise reduces the wear and tear on the cars caused by the jolting and jarring that the trains are subject to on the ordinary crossings.

It is to be understood that the form of my 55 invention herewith shown and described is to be taken as a preferred example of the same, and that certain changes in the shape, size, and arrangement of parts may be resorted to without departing from the spirit 60 of the invention or the scope of the subjoined claims.

Having thus fully described my invention, what I claim is:—

1. The combination of a track crossing

having wheel flanged gaps at the points of 65 intersection, filler blocks pivotally mounted within the gaps, a clamping block forming a section of one track, and means for normally holding the filler blocks in a vertical position and yieldably resist the pivotal 70 movement thereof.

2. The combination of a track crossing having wheel flanged gaps at the points of intersection, a section of one track being cut away forming a recess, bearings formed in 75 said recess, filler blocks pivotally mounted midway the depth of the gaps, a clamping member conforming to the shape of the recess adapted to retain the filler blocks in their bearings, and retractile springs depending from the bottom of the filler blocks adapted to normally retain them in a vertical position and yieldably resist the pivotal 80 movement thereof.

3. The combination of a track crossing 85 having wheel flanged gaps at the points of intersection, bearing openings in the ends of the rails, a recess midway the crossing, bearings formed in the edges of the recess, 90 filler blocks having journals mounted in said bearings, a clamping block for covering the recess and forming a continuation of the track, and means beneath the filler blocks for normally holding the same in a vertical 95 position.

4. The combination of a track crossing having wheel flanged gaps at the points of intersection, a recess in one track midway the crossing, bearings cut from the edges of the recess, corresponding bearing openings 100 in the ends of the rails, said openings being of an elongated shape, filler blocks having journals mounted in the bearings within the gaps, a clamping block covering the recess and holding the journals firmly in the bearings, and means disposed beneath the filler blocks 105 adapted to normally retain the blocks in a vertical position.

5. The combination of a track crossing having wheel flanged gaps adjacent the 110 points of intersection, a recess in one track midway the crossing, bearings cut from the edges of said recess, bearing openings in the ends of the rail, filler blocks within the gaps, 115 journals extending from opposite sides of blocks for reception in the bearings, a clamping block filling the recess and forming a continuation of the track, and means depending from the bottom of the filler blocks for normally retaining the blocks in 120 a vertical position and to yieldably resist the pivotal movement thereof.

In testimony whereof I have affixed my signature in the presence of two witnesses.

HAROLD W. PATTISON.
